CRUSHING AND GRINDING MACHINE

Don E. Hughes, Wayland, Mich.

Application April 1, 1940, Serial No. 327,192

11 Claims. (Cl. 83—11)

This invention relates to improvements in crushing and grinding machines.

The main objects of my invention are:

5 First, to provide a crushing and grinding machine for milling and the like having improved means for reducing stock to whatever size is desired.

10 Second, to provide a hammer mill type grinding machine having a comminuting and grading screen capable of being adjustably positioned with reference to the housing and crusher bars or hammers therein to enable stock to be reduced to any one of a number of different degrees of fineness.

15 Third, to provide a machine of the type described, wherein the means for effecting the adjustments mentioned are simple and inexpensive.

Fourth, to provide a machine having an adjustable screen of the type described and means 20 for completely sealing the latter on the grinder housing in any adjusted position thereof.

Fifth, to provide a grinding machine having means for custom grinding stock such as grains and the like to any desired grade or fineness.

25 Further objects relating to details and economies of my invention will appear from the description to follow. The invention is defined in the claims.

A structure embodying the features of my invention is illustrated in the accompanying drawings, wherein:

Fig. 1 is a fragmentary view in end elevation illustrating a swinging hammer grinding machine having incorporated therein the features of my invention.

Fig. 2 is a fragmentary view in vertical longitudinal section on line 2—2 of Fig. 1, further illustrating details of the invention.

Fig. 3 is an enlarged fragmentary view in section on line 3—3 of Fig. 2, illustrating structure for clamping the screen in one of its adjusted positions with relation to the grinder housing.

Fig. 4 is an enlarged fragmentary view in section on line 4—4 of Fig. 2, illustrating means for translating the screen longitudinally in the adjustment thereof.

Figs. 5 and 6 are fragmentary views in side elevation illustrating the main features of the invention in two other contemplated embodiments 50 thereof.

The present invention relates to a grinding and crushing machine of the swinging hammer or hammer mill type such as is commonly used in the milling of grains and for grinding and crushing many other articles in processing thereof.

Generally speaking, the invention relates to the provision of a novel type screen for such a machine, which is adjustable lengthwise thereof and is provided with apertures of different sizes selectively positionable by the adjustment of the 5 screen to regulate the size or fineness of the ground product and thereby enable custom grinding of grain and the like. More particularly, the invention includes devices of one type or the other for automatically shifting the screen and 10 positioning the same and in further devices for firmly clamping the same against the sides of the grinder housing so as to completely seal the same and prevent exit of the ground stock from the housing other than through the grinding aper- 15 tures. All these instrumentalities are actuatable and controllable from a point remote from the machine itself.

Referring to the drawings, Fig. 1 in general illustrates a grinding and crushing machine of the 20 hammer type including a grinding housing 2 having rotatable hammers 3 of known construction mounted therein. The stock to be ground is led into this housing in known manner from an upper hopper through a chute 4 past a preliminary crusher 41 and magnetic metal separator 42. Many of the details of this machine are entirely 25 conventional and will be recognized as such by those skilled in the art, hence they are not shown in detail nor described with particularity. 30

Referring to Figs. 1 and 2, the housing has the parallel vertical side plates or walls 5 each provided with an arcuate slot 6 to receive the adjustable arcuate screen 7 for longitudinal adjustment of the latter through the housing. It will be understood that the hammers of the mill coat with this screen in grinding and reducing the stock. As illustrated in Fig. 2, the screen 7 is in reality made up of a plurality of individual screen plates or sections 8 arranged end to end. These individual screens have apertures 10 of different sizes therein, the apertures in each individual screen section 8 being of the same size. Likewise, each section or individual screen is of sufficient length to extend completely over the space between the housing side walls 5, engaging the latter at the ends of the sections so as to enclose the housing.

At its lateral sides, the elongated composite screen 7 is secured by tapered pins 9 to the combined rail and rack bars 11, 12 which have rack teeth 13 engageable by the gears 14, 15 respectively. Each screen section is removably and replaceably mounted on the bars by pins 9, hence a choice is possible as to the character of the in- 55

dividual sections making up the screen as a whole. A smooth rail surface 16 is provided on the bars adjacent and parallel to each set of rack teeth to rollingly support the bars on the 5 spring mounted wheels or rollers 17, 18, which will be further referred to. Bars 11, 12 are braced at their ends by the angle irons 19, Fig. 2.

From the foregoing, it will be appreciated that upon rotation of gears 14, 15 the screen 7 is 10 translatable longitudinally of the machine on rollers 17, 18 to position any desired one of the screen sections or elements 8 across the grinding housing. The screen is resiliently carried by and elevated slightly by the rollers to prevent binding 15 of the screen with the lower side of the slots 6 through which it travels.

The gears 14, 15 are mounted on shafts 20, 21, respectively, suitably journaled at one side of the housing, the shaft 20 being driven from shaft 21 20 by means of a link belt drive 22. The shaft 21 is driven from the vertically arranged shaft 23 through meshing bevel gears 24. The shaft 23 ordinarily extends upwardly to a point remote from and usually on a floor above that on which 25 the machine is disposed, this being the conventional practice. Shaft 23 may be actuated in any suitable manner as by crank, hand wheel, motor or the like.

It will be understood that rollers 17, 18 lift the 30 screen so that its segmental surface will clear the side walls 5 of the grinding housing at slots 6 without binding. These rollers engage the rail surfaces 16 on either side of the housing to lift the screen for translation without, however, disengaging the rack surfaces 13 from the respective gears coacting therewith. To enable this, the 35 rack and gear teeth may be elongated and the slots in the housing side walls 5 made of decreased width or provided with a shoulder 25 adjacent the bars 11, 12, so as to restrain the vertical lifting of the screen and prevent its frictional engagement with the upper side of slot 6.

When the desired screening surface is operatively positioned with reference to the housing, I 40 contemplate securely clamping the same over the housing so as to prevent the escape of stock through the slot 6 accommodating the screen. To this end, I provide a pair of arcuate, vertically shiftable clamping bars 26 adjacent and inside 45 either side wall 5 of the housing. Each of these clamping bars has a pair of ears 27, preferably integral therewith, provided with a circular opening and surrounding a circular disk 28 eccentrically secured to a shaft 29. The shafts 29 are 50 located adjacent but spaced from the sides of the arcuate screen 7. The respective shafts are linked together for simultaneous rotation by means of a crank 30 connected to one thereof, a bell crank 31 connected to the other, and a rigid link 32 connecting crank 30 with one arm of the bell crank. The free arm of the bell crank is actuated by a vertically disposed rod 33 from a point adjacent the control for the shaft 23. The operating linkage for clamping the screen 60 is disposed exteriorly of the grinding housing, as illustrated in Fig. 1. Though I prefer the eccentric clamping means shown and described, it will be evident that other equivalent means could well be employed for this purpose.

70 Immediately adjacent the side walls 5 beneath the arcuate slots 6, there is disposed a pair of arcuate bars 331, see Figs. 2 and 3, one welded to each side wall and disposed immediately beneath a clamping bar 26 so as to brace and reinforce the side walls 5, as well as provide a sur-

face of considerable width against which the screen can be clamped without damaging the same. It will be understood that the clamping bars when actuated engage the screen to depress the same against the lifting action of the spring 5 loaded rollers 17 and to closely seal the same against the side wall. At the same time, the arcuate bars 26 slidingly engage the portions of the walls 5 above the screen to close the openings left by the slots above the screen, so that 10 escape of ground stock at those points is prevented.

In Fig. 5, I illustrate a modified embodiment of my invention, wherein the shifting of the screen is accomplished by means of a pair of threaded 15 parallel shafts 34 journaled on a suitable framework 35 and each having a nut 36 threadedly engaging the same, which is mounted on a side rail member 37 secured to the screen. The shafts 34 are connected for simultaneous actuation by a 20 chain belt 38 and are driven from above by a further chain belt 39 or by other equivalent means. On the opposite side of the machine, the rails 37 may be supported for translation by 25 wheels 40.

In Fig. 6, I illustrate a still further modified embodiment of my invention, wherein the screen supporting structure or frame, which is generally designated 41, is actuated in either direction by means of cables 42, 43, the latter of which 30 is trained about a pulley 44 on the machine frame. These cables pass around guide wheels 45 and are secured to a pin or lug 46 on the screen frame so as to actuate the screen for translation in an obvious manner when the cables are tensioned. The frame travels on rollers 47 at either 35 side of the housing.

The foregoing improvements make it possible for a miller to readily and quickly perform custom grinding on any of several grades demanded most commonly. In the past, in the event that a different fineness was demanded than the machine was set up to run, it has been necessary to change the screen in its entirety, which is a difficult and time consuming operation. By the provisions of my invention, change from one grade to another can be effected in an instant. The amount of actuation of the controls (not shown) for a sufficient shifting of the elongated screen requisite to change from one section or area thereof to another may be readily ascertained and suitably calibrated on the control means, thereby rendering it unnecessary to make frequent trips to the machine in adjusting the same. The aforesaid provisions are simple and inexpensive and can be incorporated in existing grinding machines without seriously altering the same.

I have illustrated and described my improvements in embodiments which are very practical. I have not attempted to illustrate or describe further embodiments or adaptations as it is believed that this disclosure will enable those skilled in the art to embody or adapt my improvements as may be desired.

Having thus described my invention, what I claim as new and desire to secure by Letters Patent is:

1. In a grinding machine of the swinging hammer type having a housing wherein hammers are rotatably mounted, an elongated arcuate screen having a plurality of longitudinally disposed sections thereof provided with grinding and grading apertures of different sizes, the apertures in a given section being of the same size, said housing having side walls provided with arcuate slots re-

ceiving the screen with substantial vertical clearance for longitudinal translational adjustment of the screen with reference to the housing, means for actuating the screen for translational adjustment to selectively position said sections relative to the housing and hammers, comprising a pair of rack bars secured to the opposite side edges thereof, gears rotatably mounted on the frame of the machine and meshing with said rack bars and means for rotating said gears from a point remote from the machine, spring means engaging said rails to elevate the screen to clear the slot when the screen is translated, and means for clamping the screen on the housing in adjusted position thereof and for sealing the openings afforded by the clearance of the slots, comprising a pair of arcuate clamping bars disposed interiorly of the housing in sliding engagement with the side walls thereof, and eccentric means rotatably mounted in the side walls and connected to said arcuate bars for actuating the latter vertically to engage and clamp the screen against the housing in the translationally adjusted position of the screen, said bars closing the opening afforded by said slots not occupied by the screen.

2. In a grinding machine of the swinging hammer type having a housing wherein hammers are rotatably mounted, an elongated arcuate screen having a plurality of longitudinally disposed sections thereof provided with grinding and grading apertures of different sizes, the apertures in a given section being of the same size, said housing having side walls provided with arcuate slots receiving the screen with substantial vertical clearance for longitudinal translational adjustment of the screen with reference to the housing, means for actuating the screen for translational adjustment to selectively position said sections relative to the housing and hammers, comprising a pair of rack bars secured to the opposite side edges thereof, gears rotatably mounted on the frame of the machine and meshing with said rack bars and means for rotating said gears from a point remote from the machine, and means for clamping the screen on the housing in adjusted position thereof and for sealing the openings afforded by the clearance of the slots, comprising a pair of arcuate clamping bars disposed interiorly of the housing in sliding engagement with the side walls thereof, and means connected to said arcuate bars for actuating the latter vertically to engage and clamp the screen against the housing in the translationally adjusted position of the screen, said bars closing the opening afforded by said slots not occupied by the screen.

3. In a grinding machine of the swinging hammer type having a housing wherein hammers are rotatably mounted, an elongated arcuate screen having a plurality of longitudinally disposed sections thereof provided with grinding and grading apertures of different sizes, the apertures in a given section being of the same size, said housing having side walls provided with arcuate slots receiving the screen with substantial vertical clearance for longitudinal translational adjustment of the screen with reference to the housing, means for actuating the screen for translational adjustment to selectively position said sections relative to the housing and hammers, spring means engaging said rails to elevate the screen to clear the slot when the screen is translated, and means for clamping the screen on the housing in adjusted position thereof and for sealing the openings afforded by the clearance

of the slots, comprising a pair of arcuate clamping bars disposed interiorly of the housing in sliding engagement with the side walls thereof, and eccentric means rotatably mounted in the side walls and connected to said arcuate bars for actuating the latter vertically to engage and clamp the screen against the housing in the translationally adjusted position of the screen, said bars closing the opening afforded by said slots not occupied by the screen.

4. In a grinding machine of the type described having a housing wherein hammers are rotatably mounted, an elongated arcuate screen having a plurality of longitudinally disposed sections thereof provided with grinding and grading apertures of different sizes, said housing having side walls provided with arcuate slots receiving the screen with substantial vertical clearance for longitudinal translational adjustment of the screen with reference to the housing, means for actuating the screen for translational adjustment to selectively position said sections relative to the housing and hammers, and means for clamping the screen on the housing in adjusted position thereof and for sealing the openings afforded by the clearance of the slots, comprising a pair of arcuate clamping bars disposed interiorly of the housing in sliding engagement with the side walls thereof, and means connected to said arcuate bars for actuating the latter vertically to engage and clamp the screen against the housing in the translationally adjusted position of the screen, said bars closing the opening afforded by said slots not occupied by the screen.

5. In a grinding machine of the type described having a housing wherein hammers are rotatably mounted, an elongated arcuate screen having a plurality of longitudinally disposed sections thereof provided with grinding and grading apertures of different sizes, said housing having side walls provided with arcuate slots receiving the screen for longitudinal translational adjustment of the screen with reference to the housing, means for actuating the screen for translational adjustment to selectively position said sections relative to the housing and hammers, and means for clamping the screen on the housing in adjusted position thereof, said last named means slidably engaging the side walls above the screen and closing the opening afforded by said slots not occupied by the screen.

6. In a grinding machine of the rotating hammer type having a housing wherein the hammers are rotatably mounted, an elongated arcuate screen having a plurality of areas thereof provided with grinding and grading apertures of different sizes, said housing having side walls provided with arcuate slots receiving the screen for selective longitudinal adjustment of the areas of the screen with reference to the housing, means for actuating the screen for said adjustment comprising a rack bar secured to the screen, a gear rotatably mounted on the frame of the machine and meshing with said rack bar, and means for rotating said gear, and means for clamping the screen on the housing in adjusted position.

7. In a grinding machine of the rotating hammer type having a housing wherein the hammers are rotatably mounted, an elongated arcuate screen having a plurality of areas thereof provided with grinding and grading apertures of different sizes, said housing having side walls provided with arcuate slots receiving the screen for selective longitudinal adjustment of the areas of the screen with reference to the housing, means

for actuating the screen for said adjustment comprising threaded means secured to the screen, an elongated screw rotatably mounted on the frame of the machine and threadedly engaging said last named means, and means for rotating said screw, and means for clamping the screen on the housing in adjusted position.

8. In a grinding machine of the rotating hammer type having a housing wherein the hammers are rotatably mounted, an elongated arcuate screen having a plurality of areas thereof provided with grinding and grading apertures of different sizes, said housing having side walls provided with arcuate slots receiving the screen for selective longitudinal adjustment of the areas of the screen with reference to the housing, means for actuating the screen for said adjustment comprising flexible cable means secured to the screen, and means for actuating said flexible cable means 10 in opposite directions to actuate the screen oppositely, and means for clamping the screen on the housing in adjusted position.

9. In a grinding machine having a housing and a grinding member operatively mounted in the housing, an elongated arcuate screen shiftably mounted on the housing and adjustable with reference to the housing to longitudinally position different areas of the screen selectively relative to the housing, said housing having side walls 25 provided with arcuate slots axially aligned with

one another for receiving the screen, means operable at a point remote from the machine to longitudinally adjust the screen to selectively position said areas, and means for clamping said screen against said side walls at the slots therein when the screen is in longitudinally adjusted position.

10. In a grinding machine having a housing and a grinding member operatively mounted in the housing, an elongated arcuate screen shiftably mounted on the housing and adjustable with reference to the housing to longitudinally position different areas of the screen selectively relative to the housing, means to longitudinally adjust the screen to selectively position said areas, and means for clamping said screen against said side 15 walls when the screen is in longitudinally adjusted position.

11. In a grinding machine having a housing and a grinding member operatively mounted in the housing, an elongated arcuate screen shiftably mounted on the housing and adjustable with reference to the housing to position different areas of the screen selectively relative to the housing, said housing having side walls provided with arcuate slots axially aligned with one another for 20 receiving the screen, means to adjust the screen, and means for clamping said screen against said side walls at the slots therein when the screen is in adjusted position.

DON E. HUGHES. 30
